UNITED STATES PATENT OFFICE.

JACOB REESE, OF PITTSBURG, PENNSYLVANIA.

MACHINE FOR ROLLING HOOPS, SHEETS, OR HOLLOW CYLINDERS.

SPECIFICATION forming part of Letters Patent No. 276,284, dated April 24, 1883.

Application filed October 11, 1880. (No model.)

To all whom it may concern:

Be it known that I, JACOB REESE, a citizen of the United States, residing at Pittsburg, in the county of Allegheny and State of Pennsylvania, have invented certain new and useful Improvements in Machines for Rolling Metal Hoops, Sheets, Plates, and Bands; and I do hereby declare the following to be a full, clear, and exact description thereof, reference being had to the accompanying drawings, forming a part thereof, in which—

Figure 1 indicates a front elevation, partly in section, of a two-high mill and its adjusting apparatus, used in rolling tubular ingots into continuous metallic bands. Fig. 2 indicates view of details of same, showing a portion of the upper removable roll, its bearings, a slide-rest upon which the roll and bearings are drawn when placing the same into or without drawing them from the housings, and also the means of securing the removable roll and bearings in the housings. Fig. 3 indicates an end view of the neck of the upper roll, with its movable bearings resting upon the slide rest or stand. Fig. 4 indicates an end view of an annular ring or collar used in securing the removable bearings in position. Fig. 5 indicates a face view of the locking-plate for securing the annular ring, the roll, and its bearings in position. Fig. 6 indicates a face view of a locking-pin used to connect the removable roll to the clutch for entering or withdrawing the same. Fig. 7 indicates a side elevation of an open housing, showing end view of the rolls, and showing some of the details of construction of the mill. Fig. 8 indicates a front elevation of a three-high mill for rolling tubular ingots into continuous metallic bands. Fig. 9 indicates a side elevation of the same. Fig. 10 indicates a side elevation of the mill, showing the ingot reduced to a continuous band.

Like letters of reference indicate like parts wherever they occur.

The objects of my invention are: the economical production of sheets, plates, hoops, and bands of iron, steel, and other metals; the manufacture of sheets, plates, hoops, or bands of greater length than can be produced by the ordinary method of manufacture; to enlarge the capacity of plants adapted for such manufacture; and, finally, to produce a finer quality of finished product.

My invention consists in the hereinafter-described means for accomplishing said objects.

I shall now describe the construction of the apparatus which I use in carrying out my improvement.

In the drawings, Fig. 1 indicates an improved two-high mill and adjusting apparatus used in my process of manufacture. Figs. 2, 3, 4, 5, 6, and 7 indicate details of the same.

A and A' indicate the housings, which are bolted securely in the usual manner to the bed-plate B.

C and C' indicate the balance-rods, which are provided in the usual manner with weighted levers at their lower ends, to cause them to press upward against the carriage c' of the upper roll, D', and force it upward when the tightening-screws d and d' are released, as will be readily understood by the skilled mechanic. These balance-rods C and C' are provided with stop-nuts, as shown in Fig. 7, which are adjusted in such a manner as to bear against the lower portion of the housing A', and relieve the upward pressure against the carriage c' when the upper roll and its bearing are brought up into line with the enlarged opening of the housing A', in order to admit their removal from the machine. The housing A is also provided with similar balance-rods, which are provided with stop-nuts, and which press constantly upward against the carriage of the upper roll until it and its bearings are brought into line to allow the removal of the roll and its bearing through the housing A'.

D indicates the lower roll, which is journaled in brasses mounted in the carriages d² and d³. These carriages are provided with rollers E and E', which are journaled in their lower surface, and which bear upon the inclined surfaces of the wedge-bar f when it is forced under or withdrawn from them by means of the action of the hydraulic ram F.

E² and E³ indicate similar rollers, which are mounted in the lower portion of the housings, and which bear against the lower and straight side of the wedge-bar f, so that it may be forced backward and forward to elevate or depress the lower roll by the action of its inclines upon the rollers E and E'.

H indicates a slide stand or rest, upon which the upper roll and the carriage c' and its rider rest and slide when withdrawn from the ma-

chine by means of the clutch I, which engages the end of the roll-neck, and is locked thereto by means of a pin, J, which is inserted through the slotted portion of the clutch and into the 5 annular slot near the end of the neck of the roll. This mode of locking permits the pin or key J to be inserted when the roll has stopped at any point of its revolution, thus greatly facilitating the locking operation.

10 K indicates a direct-acting steam-engine having its piston attached to the clutch, in order to force the same backward and forward when it is desired to enter or withdraw the roll, and its bearing from the mill, or insert them 15 into position in the same.

Fig. 2 indicates a view of the means employed to keep the upper roll and the carriage c' and its rider in place when inserted. M indicates an annular ring, which is made of sufficient width to cause its outer end to project a short distance beyond the end of the neck of the roll D' when inserted in position, as shown 20 in Fig. 2. N indicates a plate for securing the annular ring M in position. This plate is dropped into the slot R in the rest or stand H when it is desired to secure the upper or removable roll and bearing in position for the rolling operation. The housing A is constructed in the form known as a "close housing," 25 such as shown in Fig. 8, in which the opening is only of sufficient width to allow the necks of the rolls to play vertically in it, and it is provided with ordinary side brasses, in order that the brasses may remain in place when the 30 upper roll is withdrawn. The housing A' is constructed differently, as shown in Fig. 7, having an opening at its upper portion of sufficient width to allow the removal through it of the upper roll, the carriage c', and its rider 35 when they are drawn out upon the slide rest or stand H by means of the clutch. The tightening-screws d and d' may be provided with small pulleys at their upper ends, and may be operated by a friction-belt, in order to keep 40 the top roll down upon the metal when the lower roll is lowered by the action of the inclined surfaces of the wedge-bar f upon the rollers E and E'.

Figs. 8, 9, and 10 indicate a three-high mill, 45 which is especially adapted to the requirements of my process when light work is to be produced. A and A' indicate the housings, which are both provided with ordinary side brasses. B indicates the bed-plate. D' indicates the 50 upper roll; D, the lower, and D² indicates the middle roll or mandrel. This center roll is made of uniform diameter throughout, and its ends are journaled in side brasses set into the 55 housings, as is usual in such cases in three-high mills, and is kept in position by means of a plate, N', bolted to the housing A, and by the plate N and locking device described 60 in reference to the two-high mill.

Figs. 9 and 10 indicate the construction of 65 the housings more fully, showing the opening of just sufficient width to allow the withdrawal of the mandrel, which is done, as in the pre-

ceding case, by means of the clutch and apparatus shown in Fig. 1, and described in reference to the former mill. F indicates the hydraulic ram for forcing the lower roll toward the upper, as described in reference to the preceding mechanism.

The operation of my machine is as follows, to wit: By removing the plate and ring N M 70 the neck of the roll D' is exposed. The clutch I is made to embrace said neck and the pin J inserted. The roll is then withdrawn from the machine, and a hot, hollow, cylindrical ingot having its center opening of uniform diameter 80 and its walls of uniform thickness is inserted opposite the opening in the housing A', and the roll D' is returned to its normal position through the opening in said ingot. The pin J is then withdrawn, the clutch I disconnected 85 from the neck of the roll, the ring M slipped over said neck, and the plate N slipped into place in the slots in stand H. Power is then communicated to the driving mechanism. At the first step in the operation of rolling, the 90 wedge-bar is thrust inward, and the lower roll is thereby elevated. When said lower roll has attained its maximum height the wedge-bar is drawn back and the roll allowed to drop. The upper roll is then forced downward by means 95 of the screws until the space between the two rolls is taken up. The wedge-bar is then again brought into play, and the lower roll forced by degrees to its maximum height, and then dropped, and the upper roll lowered in the manner already described. This alternate movement of the two rolls is continued until the ingot has been rolled out into a sheet of the desired dimensions.

It will be observed that the movement of the 105 upper roll is solely for the purpose of taking up the space left vacant by the dropping of the lower roll.

Now, the particular advantage of this construction and mode of operation is that it 110 equalizes and distributes the strain upon the machine and its driving mechanism. This it accomplishes in the following manner, to wit: The working-necks of the rolls are connected in the ordinary manner, by wabblers with the 115 driving-pinions. Now, these pinions, in order to work to greatest advantage when the ingot has become cooled and the rolling operation 120 nearly done, must be of the same or nearly the same diameter as the rolls, and this because only in that way can the pinion-shafts, the wabblers, and the rolls work in parallel planes when the ingot is being finished. Now, if only one of the rolls is given vertical movement, the wabbler, pinion-shaft, and fixed roll 125 must be in alignment, while the wabbler of the movable roll must necessarily be, at the beginning of the operation, at considerable angle to the planes of said roll and its driving-pinion. The consequence of this is that at the beginning of the operation an immense strain is brought upon the mechanism of the upper roll, and great loss of power and wear and breakage of said mechanism are the necessary conse- 130

quence. Now, by constructing the machine so that each of the rolls may move vertically, and by operating them as described, I am enabled to begin the rolling with both wabblers at a slight angle to the planes of their respective rolls and pinions. As the operation proceeds, the upper wabbler is gradually brought nearer and nearer to the plane of its roll and pinion, while the lower wabbler is alternately at an angle with and coincident with the plane of its roll and pinion. The consequence is that at all times the strain is distributed, and the wear and tear and breakage, as well as the loss of power, are largely decreased. Practically, by this change in construction, I am enabled to save about two dollars upon each ton of metal treated.

As soon as the metal assumes an elliptic form, or enlarges upon the mandrel during the operation, a stream of water should be caused to flow between its interior surface and the surface of the mandrel, in order to remove the scale from its surface and to keep down the temperature of the mandrel. By this means the mandrel may be kept sufficiently cold for ordinary work during the rolling operation; but in some cases, where heavy work is to be produced, it may be necessary to change the mandrel, which may be readily done, and a cool mandrel may be inserted and the pressure again applied and the operation of the rolls continued until the band is finished.

In the manufacture of heavy plates and sheets the use of the two-high mill is preferable, as it would require great power to work heavy ingots on the three-high mill on account of the continual bending action which takes place in the metal when subjected to this process of rolling; but when lighter sheets and plates are to be produced the three-high mill is preferable, as the reducing action is faster, and the continuous bending action removes the scale and cleanses the surface of the metal.

My machine is especially adapted to the manufacture of steel skelps for tubing, and also for steels for structural and all other purposes wherein it is necessary or desirable to secure long lengths in the material.

When it is desired to produce polished sheets, plates, hoops, or bands, the ingot is treated as before described until it is reduced to a continuous band of the desired thickness. The mandrel is then withdrawn and the band is taken from the machine previous to cutting. This band may then be doubled over until it is in a convenient shape to handle, and conveyed to the pickling-vats and pickled. It is then washed to remove the acid from its surface, and afterward conveyed back to the machine, inserted between the housings, the mandrel is forced into position and locked, and the band rolled cold until the metal is in the desired condition.

It will be noticed that in this specification I have used the term "ingot iron." Wherever the same occurs I wish to be understood as having reference to an ingot made by a fluid

process—such as the Bessemer or open-hearth process—which ingot, when heated to a bright-red temperature, and then plunged into cold water, will not harden, as contradistinguished from a steel ingot, which will harden when so treated. The term "ingot iron," as employed by me, is that which has been adopted and defined, as before specified, by an international commission of metallurgical experts appointed by the technical societies of the United States, England, France, Germany, and Sweden. Where the word "ingot" occurs in this specification it has no reference whatever to cast-iron ingots.

The advantages of my machine over those ordinarily used are: First, the metal is always kept in the bite of the rolls from the commencement of the rolling operation, and there is an entire absence of the sudden shock, jar, and strain which come upon the ordinary mill as the metal enters and leaves the rolls at each succeeding pass; secondly, the strain comes evenly and gradually upon the mechanism, and backslashing, which is so destructive to the ordinary mill, is entirely avoided; thirdly, a high rate of speed cannot be had in the use of the ordinary mill, on account of the sudden jars, shocks, and backlash to which it is subjected; but my improved apparatus may be worked at a high rate of speed, the mill running to advantage at a speed of from one hundred to one hundred and fifty revolutions per minute, whereas the ordinary mill cannot be run over forty revolutions to advantage; fourthly, my process is automatic as far as the rolling is concerned, and a great saving is effected in the cost of skilled labor for that purpose; fifthly, the ingots may be rolled into sheets or plates at one heat, thus saving the cost of fuel and the labor for re-heating, and the loss of metal which takes place during the reheating operation; sixthly, by using ingots of a tubular or hollow cylindrical form they may be readily rolled over to secure a uniform heat in the heating-furnace, and as they expose a large surface to the action of the heat they may be heated uniformly and more readily than other shapes; seventhly, the continuously-bending action of the rolls upon the metal loosens the scale and impurities from its surface; eighthly, the facility by which long plates or bands may be produced enables me to effect a saving of from ten to fifteen per cent. of waste, which takes place in cutting sheets or plates to length which are produced by the old method; ninthly, a better and more uniform quality of metal is produced, because it may be heated more uniformly, scaled more thoroughly, rolled more uniformly, and finished at a higher temperature; tenthly, longer sheets or plates may be produced for structural and other purposes than by the use of the ordinary process of manufacture.

I am aware that it has been proposed to roll cylindrical piles formed of sections of wrought-iron welded to each other into rails, bands, tires, and sheets, and do not claim the

same for the reason that such a cylinder would not possess a homogeneous structure, owing to the different sections so welded being necessarily made from different heats by the puddling process, which can only make about five hundred pounds at a heat, whereas my ingot-iron or ingot-steel, though each ingot weighed ten tons, would be made from one and the same heat, and be absolutely homogeneous throughout. Where large plates or wide sheets are to be manufactured, such as my invention is designed to produce, the metal must be homogeneous to prevent the warping, twisting, and buckling of the plate, which, if it occurred, would prevent the proper operation of the rolls. Consequently a homogeneous ingot is essential to the practice of my process.

Having described my invention, what I claim, and desire to secure by Letters Patent, is—

1. The slotted clutch I, provided with recess in one side, and pin J, adapted to fit in said recess and into a like recess in the arti-

cle clutched, substantially as and for the purposes described.

2. The combination, with the neck of the roll D', and the stand H, provided with slots R, of the ring M and plate N, substantially as described, whereby the roll is locked in place, for the purpose set forth.

3. In a machine for rolling metals, wherein an open housing and a removable roll and bearing are used, the combination of adjustable balancing-rods, which are provided with stop-nuts to engage against the lower portion of the housings, with the removable roll and its bearings, whereby the upward pressure upon the removable roll and bearing is relieved at the point where they are to be removed through the enlarged opening of the housing, substantially as herein set forth.

JACOB REESE.
